UNITED STATES PATENT OFFICE.

JOHN S. BUTLER AND SAMUEL G. GREEN, OF THE UNITED STATES ARMY.

BIPOD.

1,375,487.

Specification of Letters Patent. Patented Apr. 19, 1921.

Application filed January 17, 1919. Serial No. 271,728.

(FILED UNDER THE ACT OF MARCH 3, 1883, 22 STAT. L. 625.)

To all whom it may concern:

Be it known that we, JOHN S. BUTLER captain, Ordnance Department, United States Army, and SAMUEL G. GREEN, lieutenant, Ordnance Department, United States Army, citizens of the United States, stationed at Washington, District of Columbia, have invented an Improvement in Bipods, of which the following is a specification.

The invention described herein may be used by the Government, or any of its officers or employees in prosecution of work for the Government, or by any other person in the United States, without payment of any royalty thereon.

Our invention relates to supports for guns, and more particularly to a support for a Browning heavy machine gun, and has special reference to the type of gun supports known as bipods (as distinguished from tripods).

The object of the invention is to provide a bipod which may be conveniently used while the operator is in a recumbent position, as when he is lying on the ground; which is simple in organization; which is relatively light in weight, yet strong and durable in use; and which embodies novel means permitting traverse and including means limiting the traverse and, also, preventing accidental disengagement of the oscillatory turret.

Subordinate objects relating to matters of specific structural improvement going to make up the ultimate perfection of the entire device will appear as the specification proceeds, and the nature of the invention more fully appears.

The accompanying drawings disclose an exemplary embodiment of the underlying principles of the invention, like reference characters indicating corresponding parts throughout the several views, which latter may be briefly described as follows:

Figure 1 is a view in side elevation of our bipod;

Fig. 2 is a view in rear end elevation, partly in section, thereof;

Fig. 3 is a fragmentary plan view of the bipod with the turret removed;

Fig. 4 is a detached detail plan view of the pivoting disk of the turret; and

Fig. 5 is a fragmentary vertical sectional view of the bipod.

55

Referring now in detail to the drawing:— 1, 1 designate the legs of the bipod, which, as shown, may be and preferably are formed as a unitary structure, from a single length of channel bar, bent intermediate its ends to form a bridge 2, and having oppositely projecting bent lower terminals 3, 3, for bearing against the ground when the bipod is in use.

A brace 4, also preferably of channel bar construction, may be used to connect the legs 1, 1 and may be conveniently positioned between the lower ends thereof as shown. The bent terminals of the brace 4 are riveted or otherwise suitably secured to the legs 1, 1.

Spikes 5, 5 are carried by the legs 1, 1 and may be secured against the bent terminals of the brace 4, as by riveting.

If desired, angle irons 6, 6 may be secured to the top of said spikes 5, 5, as by riveting. The lower bent terminals of the angle irons are substantially in the plane of the leg-terminals 3, 3 and constitute auxiliary means for bearing against the ground when the bipod is in use.

Riveted, or otherwise suitably secured to the bridge 2, are angle plates 7, 7.

A disk 8 is riveted to said angle plates, and is provided with segmental marginal flanges 9, 9, each of which has a coextensive inturned lip 10 at its top. Said segmental flanges 9, 9 are symmetrically arranged so that corresponding ends thereof are equally spaced, as shown clearly in Fig. 3. The disk is also provided with a central boss 11 through which and through the bridge 2 may pass a fastening member 12 carrying a nut 13.

Between the disk 8 and the bridge 2 is disposed a resilient tongue 14; and, desirably, the fastening member 12 projects through this tongue. The tongue carries a pin 15 projecting through a peripheral notch 16 in the disk 8 intermediate two adjacent ends of the flanges 9, 9.

The oscillatory turret comprises, in this

instance, a channel plate 17 and a cradle 18. The cradle is preferably a bow shaped plate provided, at its forward end, with a tongue 19, which is bent under and secured to the plate thus forming a loop 20. The cradle is provided, at its sides, with arms 21, 21 bent downward and under the cradle and secured thereto. By this construction of cradle, a somewhat yielding or springing support is provided for the machine gun, to take up jar and vibration and prevent them being transmitted to the legs 1, 1.

Carried on the under surface of the channel plate 17 is a pivoting member, comprising, in this instance, superposed disks 22, 23, each of which is provided with a registering central aperture 24, through which the boss 11 projects (as shown in Fig. 5). The disks 22, 23 may be secured to the member 17 by rivets 25. The disk 23 is provided with diametrically opposite tongues 26, 26. By disposing the member 17 so that the tongues 26, 26 are between the corresponding ends of the flanges 9, 9 and then turning 25 the member 17 so that said tongues pass beneath the lips 10, 10, the turret is held against accidental removal from its support. In use of the bipod, the pin 15 limits traverse of the turret, since, in the traverse of 30 the turret, the tongues 26, 26 strike against said pin. Said pin also prevents accidental removal of the turret from its support, as is evident, since, by its position, it prevents the tongues 26, 26 passing entirely from 35 beneath the lips 10, 10.

In compliance with the patent statutes, we have described, with great particularity, a specific embodiment of our invention; but the spirit of the invention is necessarily independent of the structural details, which 40 may be changed, as desired. Therefore, all modifications as come within the scope of the appended claims are within the range of our invention.

45 Having thus fully described our invention, what we claim as new and desire to secure by Letters Patent is:—

1. A bipod including a removable turret mounted for traverse, and a resiliently-supported member in the path of movement of said turret for limiting traverse and preventing accidental removal of the turret.

50 2. A bipod comprising a turret, supporting means therefor having flanges providing overhanging turret-retaining lips, and means normally preventing removal of said turret from said lips and limiting the traverse of the turret.

55 3. A bipod comprising a turret, supporting means therefor having longitudinally-arcuate flanges providing longitudinally-arcuate overhanging turret-retaining lips, and means normally preventing removal of said turret from said lips and limiting the traverse 60 of the turret.

4. A bipod comprising a turret, supporting means therefor having flanges providing overhanging turret-retaining lips, and a member normally in the path of movement of said turret for preventing removal thereof from said retaining lips and limiting the traverse of the turret. 70

5. A bipod comprising a turret, supporting means therefor having flanges providing overhanging turret-retaining lips, and a resiliently-supported member normally in the path of movement of said turret for preventing removal thereof from said retaining lips and limiting the traverse of the turret. 75

6. A bipod comprising a turret, supporting means therefor having flanges providing overhanging turret-retaining lips, and means normally preventing removal of said turret from said retaining lips, comprising a resilient tongue carrying a projection normally 80 in the path of movement of said turret.

7. A bipod comprising a movable turret, and stationary supporting means therefor having flanges providing overhanging lips, said turret carrying means movable beneath 90 said lips to hold the turret against accidental removal, and movable from beneath said lips to permit removal of said turret.

8. A bipod comprising a movable turret, and a stationary disk upon which said turret moves and having segmental flanges providing overhanging lips, said turret carrying tongues movable beneath said lips to hold the turret against accidental removal, and movable from beneath said lips to permit removal of said turret. 95

9. A bipod comprising a movable turret, and a stationary disk upon which said turret moves and having segmental flanges providing overhanging lips, said turret carrying tongues movable beneath said lips to hold the turret against accidental removal, and movable from beneath said lips to permit removal of said turret, and a movable member in the path of movement of said 100 tongues for limiting traverse of said turret.

10. A bipod comprising an oscillatory turret, and a stationary disk upon which said turret revolves and having segmental flanges providing overhanging lips, said turret carrying tongues movable beneath said lips to hold the turret against accidental removal, and movable from beneath said lips to permit removal of said turret, and a movable member disposed between two adjacent ends 115 of said flanges and in the path of movement of said tongues for limiting traverse of said turret. 120

11. A bipod comprising a rotatable turret and a stationary disk upon which said turret revolves and having segmental flanges providing overhanging lips, said turret carrying tongues movable beneath said lips to hold the turret against removal, and movable from beneath said lips to permit removal of 125 130

said turret, and a resiliently-supported member in the path of movement of said tongues for limiting traverse of the turret.

12. A bipod comprising a rotatable turret and a stationary disk upon which said turret revolves and having segmental flanges providing overhanging lips, said turret carrying tongues movable beneath said lips, to hold the turret against removal, and movable from beneath said lips to permit re-

moval of said turret, and a member limiting traverse of the turret and preventing accidental removal thereof.

13. A bipod comprising a turret mounted for traverse, said turret including a sheet metal cradle provided with a tongue at its forward end bent under and secured to the cradle, forming a loop.
